DESIGN FOR A JIG SAW PUZZLE PLAQUE

Jacobus J. Beyens, Toronto, Ontario, Canada

Application June 23, 1934, Serial No. 52,303

Term of patent 14 years

To all whom it may concern:

Be it known that I, JACOBUS J. BEYENS, a British subject, and a resident of the city of Toronto, in the Province of Ontario, in the Dominion of Canada, have invented a new, original, and ornamental Design for a Jig Saw Puzzle Plaque, of which the following is a specification, reference being had to the accompanying drawing, forming part thereof.

Figure 1 is a face view of a plaque and Figure 2 is a cross section taken thru the centre thereof.

The decorative design consists of a round

plaque having upon a face thereof a centrally disposed blank space of a rectangular shape defined by a black border and encompassed by a series of black concentric circles providing interspaces which are filled with alternately occurring red and blue discs, circularly arranged.

I claim:

The ornamental design for a jig saw puzzle plaque, as shown and described.

Signed at Toronto, Ontario, Canada, this 20th day of June 1934.

JACOBUS J. BEYENS.
